US0D1073772S

(12) **United States Design Patent** (10) **Patent No.:** **US D1,073,772 S**
(45) **Date of Patent:** **** May 6, 2025**

(54) **PROJECTION SCREEN**

(71) Applicant: **Bloomsbury Lab. Co., Ltd.**, Seoul (KR)

(72) Inventors: **Yo Sup Kim**, Seongnam-si (KR); **Seon Young Cheon**, Seongnam-si (KR)

(73) Assignee: **Bloomsbury Lab. Co., Ltd.**, Seoul (KR)

(**) Term: **15 Years**

(21) Appl. No.: **35/518,321**

(22) Filed: **Mar. 13, 2023**

(80) **Hague Agreement Data**

Int. Filing Date: **Mar. 13, 2023**

Int. Reg. No.: **DM/227985**

Int. Reg. Date: **Mar. 13, 2023**

Int. Reg. Pub. Date: **Sep. 15, 2023**

(51) **LOC (15) Cl.** **16-05**

(52) **U.S. Cl.**

USPC **D16/241**

(57) **CLAIM**

The ornamental design for a projection screen as shown and described.

DESCRIPTION

1.1 is a front perspective view of a projection screen, showing our new design;

1.2 is a front view;

1.3 is a rear view;

1.4 is a left view;

1.5 is a right view;

1.6 is a top view;

1.7 is a bottom view; and

1.8 is a back perspective view.

The broken lines in the drawings depict portions of the projection screen and form no part of the claimed design.

1 Claim, 7 Drawing Sheets
